ROBERT TROST, OF SAN FRANCISCO, CALIFORNIA.

METHOD AND MEANS FOR CONSTRUCTING FORMS FOR CONCRETE.

1,420,166.

Specification of Letters Patent. Patented June 20, 1922.

Application filed June 8, 1921. Serial No. 475,886.

To all whom it may concern:

Be it known that I, ROBERT TROST, a citizen of the United States, and resident of the city and county of San Francisco and 5 State of California, have invented new and useful Improvements in Methods and Means for Constructing Forms for Concrete, of which the following is a specification.

My invention refers more particularly to 10 the method and means employed for constructing wooden forms within which reinforced concrete is to be molded and especially for the building of concrete walls wherein two wooden sides are supported in 15 position in which it is desired to mold the concrete, and when properly spaced apart form a space in which the concrete is poured and allowed to set. It has heretofore been customary to hold said wooden forms in 20 spaced relation by employing tie wires therebetween which tie wires are twisted within the said space and left in place in the concrete after it has been molded between the said sides and the sides removed. These 25 wires, however, form no material part of the reinforcing material which must extend in planes at right angles to the general direction of the said tie wires. These tie wires remaining in the concrete cause leaks 30 and rust stains which detract greatly from the appearance of the walls or buildings so constructed. In my invention I employ tie wires lying straight and which may be readily withdrawn from the concrete after 35 it has set and when the forms are removed.

By referring to the accompanying drawings my invention will be made clear.

Fig. 1 is a perspective view of a pair of 40 form sides between which a concrete wall is to be formed.

Fig. 2 is a vertical cross section through a portion of said walls and with one of the tie wires thereof shown in perspective.

Fig. 3 is a side view of one of the tie wires. 45 Throughout the figures similar numerals refer to identical parts.

The form within which the concrete walls are to be molded is comprised generally of two sides indicated in the figures by the 50 numerals 1, 2, respectively, formed by boards tied together by strut members 3, 4, 5, respectively, and the struts so formed are then held together by the posts 6, 7, 8, 9, respectively. The completed sides thus 55 formed are then set in position with spacing members 10 located at occasional intervals,

which spacing members are under compression when the forms are drawn together by my tie wires. These tie wires I arrange as shown in detail in Figs. 2, 3. The wire 60 being first formed of U shape, bent as shown in Fig. 3 and holes being drilled through the sides 1 and 2 for said wires at 11, 12, 13, 14, respectively. This work is preferably 65 done by a bit or drill sufficiently long to extend from one side across the space and through both sides. The U shape wire is then passed through the holes 11, 12, embracing between its sides the strut 3 and member 6 and thence passed over the strut 70 4 and member 8. In the member 8, I drive a wire nail or other circular pin 15 and twist both ends of the U wire which now project adjacent to said nail or pin around the nail and parallel to each other and with the 75 wraps of the two ends adjacent.

The U shape tie wire is formed of the two legs 16, 17, which are connected together at one end at 18 and the ends of the sides 16, 17, I have shown as 16' and 17', respectively. 80 After giving one turn to these two ends 16' and 17' around the pin 15 by hand to temporarily hold them, I clamp the ends as with suitable pliers, and wind them about the pin 15 which latter they tightly grip as the winding proceeds and the pin may at such times be turned with the wires. The result is a tight gripping tie which draws the sides 1 and 2 together against the spacing member 10 which is now in compression, see Fig. 2. 90 The sides 1 and 2 will now be spaced a proper distance apart to receive the concrete as determined by the length of the spacing member 10. When the concrete has been placed between the sides 1 and 2 and 95 has set or hardened, the legs 16, 17, may be cut, preferably where they project through the wooden sides at 19, 20, as with a cold chisel or pliers and the legs 16, 17, may then be withdrawn by pulling on the tie wire 100 from the opposite side of the said cuts. The wire is then readily withdrawn from the concrete and a finished coat of neat cement or other suitable covering may be now employed to face the wall by troweling, cement 105 gun or otherwise. This completely closes the holes which have been left in the wall by the withdrawal of the wire 16, 17. The removal of the wires prevents iron stains showing on the surface after the wall has 110 been weathered as is always the case where the wires are left in the wall and cut off.

short where they come through. While I have shown no reinforcing bars in place within the form, it is understood that they may be employed in the usual well known ways.

It will be noted that my pin 15 forms in effect a capstan about which the wire is wound binding the wire ends tightly together and placing the legs 16, 17, in sufficient tension to hold the form sides rigid; these legs have a straight pull, as distinguished from tie wires as heretofore employed wherein the wires are twisted throughout the portion which is subject to tension strains. The employment of my ties results in a more rigid holding of the form sides than heretofore. In employing the method of my invention the form sides are first constructed and then set in place which results in a very much cheaper and accurate form construction than where the forms are built up in their final position board by board and the tie wires placed during the assembling of the boards.

25 Other advantages will appear to those skilled in the art from a study of my specification and drawings.

I claim:

1. The method of constructing forms for reinforcing concrete comprising a plurality of sides, which consists of first setting the built up sides in position and then passing holding wires of U shape having two straight legs through the said sides and twisting the parallel ends of said wire around a member adapted to rotate and then clamping the two ends simultaneously and rotating them and

the said member to wind the wire and cinch the sides in assembled position.

2. The method of building a reinforced 40 concrete structure which consists of preparing wall forms and binding them together as set forth in claim 1, after which a cement mixture is placed between said walls and allowed to harden, the wire legs are then cut 45 close to the form and pulled out from the opposite side and forms removed, then a finish coat of cement or the like is applied over the concrete face whereby the holes left by withdrawing the wires are plugged. 50

3. A tie for preparing forms for reinforced concrete which tie consists of wire bent substantially U shape adapted to pass around a truss on one side of the form and pass across the space between the form sides and embrace a truss of the opposite side of the form, a pin in said last named truss and said ends brought together and wound parallel to each other and around said pin. 55

4. A tie for preparing forms for reinforced 60 concrete which tie consists of wire of substantially U shape adapted to pass around a truss on one side of the form and pass across the space between the form sides and embrace a truss of the opposite side of the form, 65 a pin in said last named truss and said ends brought together and wound parallel to each other and around said pin, in combination with form sides and spacing members located at intervals between the said sides 70 adapted to be held in compression by said ties.

ROBERT TROST.
